J. H. SEWELL

TOBACCO PIPE CLEANER

Filed March 16, 1925

INVENTOR
JOHN H. SEWELL,
by Fetherstonhaugh & C.
ATTYS.

UNITED STATES PATENT OFFICE.

JOHN HENRY SEWELL, OF SASKATOON, SASKATCHEWAN, CANADA.

TOBACCO-PIPE CLEANER.

Application filed March 16, 1925. Serial No. 15,998.

To all whom it may concern:

Be it known that I, JOHN HENRY SEWELL, a subject of the King of Great Britain, and a resident of the city of Saskatoon, in the 5 Province of Saskatchewan, Canada, have invented certain new and useful Improvements in Tobacco-Pipe Cleaners, of which the following is the specification.

My invention relates to improvements in 10 tobacco pipe cleaners and the object of the invention is to construct a device which can be attached to the stem of a pipe or cigarette or cigar holder and connected to any compressed air line whereby any obstruction in 15 the pipe or holder will be cleared out by the air passing therethrough.

My invention consists of a device constructed and arranged all as hereinafter more particularly described and illustrated 20 in the accompanying drawing in which:

Fig. 1 represents a side elevation of my device partly in section showing it applied to the stem of a pipe and also showing the nozzle of the air line connected with the device.

Fig. 2 is a plan view thereof.

Fig. 3 is a longitudinal section thereof, and

Fig. 4 is a cross sectional view through 30 the line 4—4 Figure 2.

Like characters of reference indicate corresponding parts in the different views.

1 is the casing constructed of any suitable 35 rigid material and preferably tapering from one end to the other, the smaller end having a reduced neck formed thereon. 3 is an insert of resilient material such as rubber adapted to receive the stem of the pipe or cigarette or cigar holder. 4 are lugs extending outwardly from the member 1 to 40 which are pivotally connected the arms 5, the inner ends of such arms being provided with shoulders 6 which are adapted to engage the member 1 when the arms are extended, thus limiting the movement of such 45 arms. 7 is the air line and 8 is the nozzle thereof, such nozzle 8 being designed to receive the neck 2 of the member 1.

In using my device the pipe stem 9 is inserted into the interior of the insert 3 and

by pressing the pipe stem securely into such tapered interior a tight joint is constituted between the stem and the resilient insert. The neck 2 of the member 1 is now applied to any air line nozzle 8, such as those used in 55 any garage or service station for the purposes of inflating tires.

When the neck 2 is applied to the nozzle 8 in the manner above described the air will be forced through the interior of the resilient insert 3, through the stem of the pipe, thus removing any obstruction or clearing out any nicotine therein and eventually blowing it out of the bowl of the pipe.

The construction of the nozzle 8 has not 60 been shown as it is identical to that used for inflating tires, the neck 2 merely being applied to the nozzle in place of the neck of the tire valve.

When the device is to be used the arms 5 70 are extended in order that the member 1 may be pressed down by the fingers engaging such extending arms so that the neck 2 enters the nozzle 8. When the device is not in use the arms 5 are swung inwardly into 75 the position illustrated in dotted lines in Figure 2.

From the above description it will be apparent that I have devised simple and effective means of cleaning a pipe or cigarette or 80 cigar holder by air, and, moreover, have devised one that is compact and which can be readily carried.

What I claim as my invention is,

1. A pipe cleaner comprising a tubular 85 casing having a neck at one end, and a hollow insert of resilient material disposed in the interior of the casing.

2. A pipe cleaner comprising a tubular 90 casing having a neck at one end and a hollow insert of resilient material disposed in the casing, the interior of said hollow insert tapering from one end to the other.

3. A pipe cleaner comprising a tubular 95 casing having a neck at one end, a hollow insert of resilient material disposed in the interior of the casing, and means for holding the casing.

4. A pipe cleaner comprising a tubular 100 casing having a neck at one end, a hollow

insert of resilient material disposed in the interior of the casing, and collapsible means for holding the casing.

5. A pipe cleaner comprising a tubular casing having a neck at one end, a hollow insert of resilient material disposed in the interior of the casing, and swingable arms hinged to the casing.

6. A pipe cleaner comprising a tubular casing having a neck at one end, a hollow insert of resilient material disposed in the casing, the interior of said hollow insert tapering from one end to the other, and swingable arms hinged to the casing. 10

JOHN HENRY SEWELL.
